(57) **CLAIM**

The ornamental design for a cooler as shown and described.

DESCRIPTION

FIG. 1 is a first top perspective view of a cooler, showing my new design;

FIG. 2 is a bottom perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is bottom plan view thereof;

FIG. 9 is a partially enlarged view thereof, taken from FIG. 2;

FIG. 10 is another partially enlarged view thereof, taken from FIG. 2; and,

FIG. 11 is a second top perspective view thereof, shown with the handle in lowered condition.

The broken lines in the drawings are for the purpose of illustrating portions of the cooler that form no part of the claimed design. The dot-dash broken lines of FIGS. 2, 9, and 10 are included to show partially enlarged views only and form no part of the claimed design.
